UNITED STATES PATENT OFFICE.

JOHN ACKERMAN, ACKBER O. MITCHELL, AND FRANK M. UNDERWOOD, OF COLUMBUS, OHIO.

SAW-MILL DOG.

SPECIFICATION forming part of Letters Patent No. 274,099, dated March 20, 1883.

Application filed January 20, 1883. (No model.)

To all whom it may concern:

Be it known that we, JOHN ACKERMAN, ACK-
BER O. MITCHELL, and FRANK M. UNDER-
WOOD, citizens of the United States, residing
5 at Columbus, in the county of Franklin and
State of Ohio, have invented a certain new
and useful Improvement in Saw-Mill Dogs, of
which the following is a specification.

Our invention relates to improvements in
10 saw-mill dogs where both an upper and lower
dog are used to hold the log on the head-block;
and the objects of our improvements are, first,
to provide, in connection with a vertical rack
secured to the side of the standard, adjustable
15 dogs capable of holding a log of any thickness
or its last board; second, to provide a pivoted
rack carrying dogs capable of being swung
thereon to the rear, and thus out of the way.
We attain these objects by the mechanism ill-
20 strated in the accompanying drawings, in
which—

Figure 1 is a side elevation of a head-block
with a dog set to hold a square piece of tim-
ber. Fig. 2 is a similar view of a head-block
25 having the rack-bar, with the dogs thereon,
swung around out of the way toward the rear
of the standard. Fig. 3 shows a portion of
the operating-lever, with the cogs thereon, in
engagement with the rack-bar. Fig. 4 shows
30 a portion of the rack with the upper dog, its
frame and clamping-bolt, and lever.

Similar letters refer to similar parts through-
out the several views.

A represents a standard secured to the head-
block B in the usual manner. To the stand-
ard A is attached, by means of two perforated
35 arms or eyebolts, b b, projecting respectively
from near the top and bottom of the standard
and at right angles to the face thereof, a bar,
40 C, having rack-teeth on its side. This bar C
terminates at both ends in short cylindrical
journals or pivots, which pass through the
holes in the arms b b. Adjoining said journals
45 the rack has shoulders C², produced by cutting
away the metal to form said pivots. The
shoulders rest against the arms b b, and by
this mode the rack-bar is held in place against
the side of the standard A. From the front
50 of this bar C is made to project an upper dog,

D, of the usual shape. It is secured to a flat 50
metal plate, e, so bent or formed as to be
adapted to inclose three sides of the bar. The
ends of plate e extend far enough beyond the
teeth on the bar to allow of their connection by
55 three bolts, which pass in front of the rack. The
central connecting-bolt, f, supports a cogged
lever, E, having three cogs thereon adapted to
engage with the teeth on the side of the rack-bar,
as shown in Fig. 3, by means of which the dog
60 is held at any desired height on the bar. The
end of the bolt f carries a nut provided with a
handle, f', by which it may be tightened suffi-
ciently to slightly spring the cheek-pieces
65 formed by the end of the dog-carrying plate e,
and, by forcing the cheek-pieces against the
hub of the said levers, prevent the accidental
release of the cogged lever E. To the lower
70 cylindrical end of the bar C a lower dog, F, is
firmly secured, said dog being bent outwardly
to prevent the head-block from interfering
with its movements. By elevating the handle
75 of the lever until near a vertical position the
three cogs on the lever are made to clear the
rack and allow the upper dog, D, with the
bearing-plates e, to ascend or descend at the
will of the operator. When the upper dog, D,
80 strikes the log or block of wood the handle of
the lever is pressed down until its free end as-
sumes a position below its pivot, which causes
the cogs on the lever to re-engage with the
85 rack and raise it until its top shoulder meets
the upper arm, b, the same movement that
is made to lower the upper dog, D, raising the
lower dog, F, until their sharp points sink into
the wood and hold it fast. When it is desired
90 to place a new log on the head-block the rack-
bar having the dogs thereon is swung to the
rear, as shown in Fig. 2, the small cylindrical
ends of the bar being free to rotate in the bear-
ings in the arms b of the standard.

Having now fully described our invention,
what we claim, and desire to secure by Letters
Patent, is—

1. The combination of a saw-mill standard
and journal-bearing arms b, projecting from the
95 top and bottom thereof, with a rack-bar hav-
ing cylindrical journals at each end, a dog, F,
at its lower end, and a movable dog adapted

to be secured upon said rack, substantially as and for the purpose described.

2. The combination of a saw-mill standard, A, and journal-bearing arms b, projecting from the side thereof, with a rack-bar having cylindrical journals at each end, a lower dog, F, secured theron, and adjustable dog D, adapted to have its hooked point turned with the rack

from the front of the head-piece, substantially as and for the purpose described.

JOHN ACKERMAN.

ACKBER O. MITCHELL.

FRANK M. UNDERWOOD.
